THREAD MILLING MACHINE

Albert J. Prance, Detroit, Mich., assignor to
 Murchey Machine & Tool Company, Detroit,
 Mich., a corporation of Michigan

Application February 2, 1942, Serial No. 429,240

3 Claims. (Cl. 90—11.56)

The present invention relates to thread milling machines.

Among the objects of the present invention is a thread milling machine which is fully automatic in its operation, is economical to construct and does not easily get out of order.

Another object is a machine which will produce a more accurate and more finely finished thread than is the case with known thread millers.

Another object is a thread miller which, when adjusted for a particular operation will duplicate the work substantially indefinitely without further adjustment.

Still other objects and advantages will be apparent to those skilled in the art upon reference to the following description and the accompanying drawings in which

Figure 1 is an end elevation, partly sectional, as from the right of Figure 3.

Figure 2 is an end elevation, partly sectional, as from the left of Figure 3.

Figure 3 is a central vertical sectional view, with parts in elevation.

Figures 4 and 5 are sectional views of certain details of construction.

Figure 6 is a partial rear view of the machine.

Figure 7 is a sectional view showing a detail of construction.

Figure 8 is a plan view of the fluid circulation elements, the connecting conduits being omitted for the sake of clarity.

Figure 9 is an electric wiring diagram, and Figure 10 is a fluid circulation diagram.

In the drawings, a suitable base 10 serves as a housing of various elements and also as a support, at one end, of the cutting spindle and associated elements and, at the other end, of the work supporting slide and its associated parts.

The latter may be and preferably is a simple sliding table 11 movable longitudinally of the base toward and from the cutter by means of a suitable hand wheel 12 and its pinion 13 and rack 14.

It is to be understood that suitable work supporting jigs (not shown) will be used in mounting the work piece thereon; an end of such a piece being shown in Figure 3 at 15.

The sole function of table 11 is work support and movement into and from a suitable location for threading.

Mounted upon the base 10 and in alignment with the table 11 is a frame member 20 pro-

vided with bearings 21 in which is mounted for rotation a cylindrical sleeve 22 bored eccentrically and carrying a second cylindrical sleeve 23 also bored eccentrically. Within the eccentric bore of sleeve 23 and carried in suitable antifriction bearings 24 is a tool carrying spindle 25, an inside threading milling cutter being shown at 26.

The spindle 25 is driven by means of a suitable sprocket 30 and link belt 31 from a gear or sprocket 32 (see Fig. 4) keyed to a short shaft 33 which is driven, through gears 34 and 35 and shaft 36, from the pulley 37, the latter being in turn driven through belt 38 by the electric motor 39.

In order to provide for the lateral or translatable movement of the spindle 25 (to be described) without interference with the drive thereof, the driving connection from motor 39 to the spindle is arranged to permit such movement, and such arrangement is shown in Figures 2 and 4.

In these figures, the bearing supporting members 36a are stationary parts of the supporting base 10 and have fixed in suitable openings a sleeve 36b serving to support the shaft 36 in suitable antifriction bearings 36c. This sleeve 36b also serves as a shaft or spindle upon which are rotatably mounted the arms 33a of the bearing support 33b, having mounted therein the shaft 33, suitable antifriction bearings 33c being provided. The assembly of gears 32 and 34 with shaft 33 is, therefore, movable around the axis of shaft 36 but is supported by the adjustable distance rod or link 30a, and which consists of an upper eye member 30b and a lower eye member 30c connected together by a threaded shaft 30d. These eye members fit over the spindle 25 and shaft 33 respectively and maintain the proper distance between the sprockets 30 and 32 as the spindle moves.

A variation in the drive speed for the spindle 25 is provided for by mounting the motor 39 upon a vertically swingable platform 39a to which is attached a link 39b in turn connected to a threaded shaft 39c coaxial with the bandwheel 39d. The pulley 38a is so constructed that its flanges move toward each other as the motor 39 and its platform are lifted.

As indicated above, the spindle 25, in addition to its rotative movement is also movable laterally in order to feed the cutter toward and from the work. This lateral or translatable movement is produced by the relative rotation of the two

eccentrically bored sleeves 22 and 23, and such relative rotation is produced by mechanism shown in Figures 3 and 7.

In these figures, the sleeve 22 is shown as slotted peripherally at 22A and has fixed to it along the slot, the bars or rails 22B, these being carried by the end members 22C suitably secured to the sleeve. And between these rails 22B and fixed thereto are blocks 22D carrying the screws 22E, projecting toward each other and movable to adjust accurately their positions. These screws 22E serve as stops for an arm 23A mounted upon sleeve 23 and projecting from slot 22A between rails 22B and adapted to coact with the stop screws.

Loosely mounted upon sleeve 22 is a worm gear 50 located adjacent the rails 22B and provided with laterally extending fingers 50A spaced sufficiently to embrace closely the arm 23A whereby to move the latter between the stop screws 22E, when said gear is actuated, and thereby move the sleeve 22 as a unit with sleeve 23. Further, in order to provide against movement of sleeve 23 until the arm 23A reaches one of the stop screws 22E, stationary brake means for sleeve 23 is provided.

This brake means is shown in Figures 2 and 3 as a brake shoe 51 anchored to the housing 20 as by the screw 52.

The worm gear 50 is driven by a suitable worm on shaft 53 in turn driven through the small gear 54 meshing with a large gear 55 fixed to shaft 56 mounted in the housing or frame 20 of the machine. The outer end of shaft 56 has fixed thereon a small pinion 57 which is adapted to coact with a rack 60, longitudinal movement of which produces the relative movement of the sleeves 22 and 23 and also rotation of these sleeves as a unit.

Figure 6, showing a rear view of the machine, shows the rack 60 and the pressure fluid cylinder 61 within which is a piston (not shown) connected by rod 62 to the rack and actuated by supplying fluid under pressure to either end of the cylinder through the pipes 63.

In the operation of the machine, as thus far described, when an inside thread is to be milled, the work piece 15 is moved into position over the cutter 26 which is centered with respect to the work because of the relative position of sleeves 22 and 23.

When the machine is then put into operation by setting up the rotation of spindle 25 and starting the operation of rack 60, the worm gear 50 starts to rotate and, through fingers 50A, partially rotates sleeve 23 within sleeve 22, the amount of rotation depending upon the travel of arm 23A between the stop screws 22E, for example, from the position 23AA in dotted lines to the full line position of 23A. In this partial relative rotation, the sleeve 22 is held by the brake 51 until the arm 23A strikes the stop screw and therefore provides for the lateral movement of the spindle 25.

This lateral movement is adjusted by the screws 22E and is the feed of the cutter into the work and therefore the depth of the cut.

When the arm 23A strikes the stop screw 22E, the gear 50 continues to turn the sleeve assembly for slightly more than a complete revolution while feed of the cutter lengthwise of the work is accomplished through the action of a lead screw 70 carried by the sleeve 22 and stationary nut 71 fixed to the frame structure 20.

The rack operation and control is effected

through the means shown in Figures 8, 9 and 10, in which (in Fig. 8) there is shown a motor 90 directly coupled to a suitable pump 91, which is arranged to draw suitable fluid from a tank 92 serving as a base upon which the motor, pump and other elements may be mounted. The pump 91 draws its fluid from tank 92 through the pipe 93 provided, preferably, with a screen 94.

From the pump 91 the fluid is conducted to a magnetically actuated valve V to the port C and from the valve V is conducted through pipes D and E to one end or the other of the cylinder 61, depending upon whether the valve is in position to connect port C with port A, from which leads pipe D, or port B, from which leads pipe E. The fourth port T is connected to a pipe T1 leading back to the tank 92.

In the valve V, the mechanism is so arranged that the ports A and B are alternately connected to port C and port T. When it is desired to actuate the rack 60 in a thread cutting operation, the valve V is set to connect the pump discharge into port C with the port A, whereupon fluid is forced directly to the end B1 of cylinder 61. At the same time, port B is connected to port T for the discharge of fluid from the end A1 of the cylinder back to the tank 92.

This discharge, however, is regulated and throttled, whereby to control the speed of movement of the rack. This throttling and control is provided for by the several valves F, G, H and I, of which the valve F is a check valve allowing fluid to flow from the pump to the cylinder, but preventing back flow.

The valve G is a cam operated valve actuable by a cam 60A carried by the rack 60. This valve G is closed or nearly so when the rack is in starting position. If it is desired to provide the rack with an initial slightly higher speed, the cam 60A may slope slightly upward toward the left end (Fig. 10). At or near its other end it slopes sharply upward so as to allow quick and full opening of the valve.

The valves H and I are hand-controlled and dial set, and calibrated to indicate the speed of rack movement. Of these, the valve H is arranged to pass less fluid than the valve I.

When the fluid flow is beginning into end B1 of the cylinder, the discharge from end A1 is through pipe A2 to the valve H, since both valves F and G are closed to its passage. From valve H the flow is through pipe H1, and pipe E back to port B of valve V which is connected to port T and through pipe T1 to tank 92. As soon, however, as the rack 60 has moved far enough to allow the cam 60A to open or permit the opening of valve G, the flow is through both valves H and I, but chiefly through valve I, since the valve G is open. The flow is, of course, through valve H, pipe G2, valve G, pipe G1 to port B, to port T and thence to the tank 92. Consequently, the rack may move at a higher speed.

When it is desired to return the rack 60 to the starting point, the valve V is set so that the port C is connected to the port B and port A connected to port T. In this position of the valve V, fluid passes from the pump through pipe E, check valve F, and directly to the end A1 of cylinder 61, while the fluid from end B1 of the cylinder flows unrestricted through pipe D, valve V, and pipe T1 to tank 92.

In addition to the several elements of valve V which have already been mentioned, means is also provided for permitting the pump 91 to discharge directly back to the tank during the period when

the rack 61 is at rest. Such means is indicated in Figure 10 by the conduit 91A.

In Figure 8, there is also shown a second pump 100, belt-driven by motor 90 and adapted to draw cutting fluid from tank 101 (see Fig. 3) and through a suitable nozzle (not shown) flow it over the work and cutter. The pipe 102 is shown (see Fig. 3) as the point of attachment of the nozzle.

In Fig. 9, the power supply lines P lead to the transformer P1, and thence to a multiple solenoid switch S to which are connected the solenoids operating the valve V, a pair of rack operated switches, a starting switch and a quick return switch.

In the diagram shown in Figure 9, the valve V is shown diagrammatically being represented as a pair of simple valves actuated by solenoids.

When it is desired to start operation of the rack 60, the rack switch K is held open by a suitable cam on the rack, the button L is pressed and completes a circuit through L2, L1, S1, solenoid S2, and L3. This circuit closes contacts M and M1 and completes the circuit L2, M1, M2, solenoid M3, L3, thereby operating valve V to start the rack and allowing switch K to close.

At the end of the rack travel, a suitable plate or cam thereon strikes and closes rack switch N, and thereby establishes the circuit through solenoid S3, this circuit being L2, N1, N, N2, S3 and L3 and closing contacts R and R1 and opening contacts R2, the latter breaking the holding circuit for solenoid S2.

Contacts R1 complete a holding circuit for solenoid S3, which circuit is L3, R1, K1, switch K, N1, L2.

Contacts R complete a circuit L2, R, W1, valve solenoid W, W2, W3, L3, thereby reversing the valve V and consequently the motion of rack 60.

Upon reaching the end of the return stroke, the switch K is opened to break the holding circuit and allow solenoid S3 to become deenergized and thereby reestablish the idle position.

If for some reason, it is desired to return the rack after a part stroke, the button X is pressed. The effect of this is to thereby establish a circuit L2, X, X1, S3, L3. This, of course, has the same effect as described above for the switch N.

It is to be understood that the invention may

be embodied in other specific forms without departing from the spirit or essential attributes thereof, and it is desired that the present embodiment be considered in all respects as illustrative and not restrictive; reference being had to the appended claims rather than to the foregoing description to indicate the scope of the invention.

I claim:

1. In a thread milling machine, having a pair of eccentric sleeves, one within the other, and a cutter carrying spindle rotatably mounted within said sleeves, means for relatively rotating said sleeves and then rotating said sleeves as a unit, said rotating means including a reversible hydraulic motor having cam actuated means for changing the speed thereof at a predetermined time during the forward or feeding portion of the cycle of operations.
2. In a thread milling machine, having a pair of eccentric sleeves, one within the other, and a cutter carrying spindle rotatably mounted within said sleeves, means for relatively rotating said sleeves and then rotating said sleeves as a unit, said rotating means including a reversible hydraulic motor having means for reversing the flow of fluid to and from said motor whereby to reverse said motor, cam actuated means for throttling the outflow of fluid whereby to regulate the speed of said motor and means for changing the degree of throttling during the forward or feeding portion of the cycle whereby to change the cutting feed.
3. In a thread milling machine, having a pair of eccentric sleeves, one within the other, and a cutter carrying spindle rotatably mounted within said sleeves, means for relatively rotating said sleeves and then rotating said sleeves as a unit, said rotating means including a reversible hydraulic motor having cam actuated means for changing the speed thereof at a predetermined time, said speed changing means consisting of a plurality of valves capable of passing different amounts of fluid and connected to the outflow of said motor, and means for blocking the flow through one of said valves during part of the operation of said motor and then opening said valve during the remaining part.

ALBERT J. PRANCE.
